UNITED STATES PATENT OFFICE.

WILLIAM RANDOLPH SMITH, OF ERDA, UTAH.

BALANCING AND STEERING DEVICE FOR AIRSHIPS.

1,003,530.

Specification of Letters Patent. Patented Sept. 19, 1911.

Application filed June 18, 1911. Serial No. 633,982.

To all whom it may concern:

Be it known that I, WILLIAM R. SMITH, a citizen of the United States, residing at Erda, in the county of Tooele and State of

5 Utah, have invented certain new and useful Improvements in Balancing and Steering Devices for Airships; and I do declare the following to be a full, clear, and exact description of the invention, such as will enable others skilled in the art to which it

10 appertains to make and use the same.

This invention relates to improvements in balancing and steering devices for air ships.

One object of the invention is to provide 15 a balancing and steering device for air ships which is adapted to be lowered as the ship rises in the air and to be raised or drawn up as the ship descends and approaches the ground.

20 Another object is to provide a combined rudder and balancing weight of this character which when in a lowered position will provide an effectual ballast to prevent the ship from careening or overturning and 25 which may be readily turned to steer the ship in the desired direction.

With these and other objects in view, the invention consists of certain novel features of construction, combination and arrangement of parts as will be more fully described and particularly pointed out in the appended claims.

In the accompanying drawings:—Figure 1 is a side elevation of my combined balancing weight and steering device; Fig. 2 is an enlarged vertical sectional view of the same with parts broken away; Fig. 3 is a cross sectional view on the line 3—3 of Fig. 2.

My improved balancing and steering device may be applied to the air ship in any suitable manner and in any suitable position and comprises a vertically disposed tubular casing 1 which is formed in two sections bolted together as shown and preferably has 45 a square outer surface and a circular bore or passage 2. The upper and lower ends 3 of the casing 1 are reduced and of cylindrical form and provided with metal ferrules 3^a to engage bearing sleeves arranged in suitable supporting bars 4 which form part of the frame of the air ship. In two opposite sides of the casing 1 are formed alined vertically disposed slots 5 the purpose of which will be hereinafter described.

55 Slidably mounted in the casing 1 is a combined rudder and weight supporting shaft

6 which may be of any suitable length. On the shaft 6 at diametrically opposite points are formed laterally extending guiding and operating lugs 7 and 8 which project 60 through the slots in the casing. On the end of the lug 7 is secured a guide block 9 which engages the outer side of the casing as shown.

To the lug 8 is connected one end of a 65 raising and lowering cable 10 which passes upwardly and around a guide pulley 11 revolubly mounted on a suitable part of the frame of the ship as shown. The other end of the cable 10 extends downwardly to within convenient reach of the operator and may be secured in any suitable manner.

On the lower end of the shaft is secured a combined rudder and balancing weight 12 which may be of any suitable size and 75 weight and which is preferably shaped as shown, and is adapted to be raised and lowered and turned to the desired position.

The rudder is turned by means of a handle 13 which is secured to the casing 1 80 at any desired point within convenient reach of the operator preferably by being provided with a bifurcated head clamped into operative engagement with the casing by a clamping bolt 14, which permits the 85 handle to be shifted to the desired position. In the handle is formed a slot 15 through which the lug 8 and cable 10 may pass in raising and lowering the shaft 6.

By thus arranging and supporting the 90 balancing weight and rudder 12 the same may be gradually lowered by the operator as the machine leaves the ground and rises in the air and when thus lowered may be turned by the handle to steer the ship in the 95 desired direction. When the weight and rudder is in its lowered position the same provides an efficient and reliable ballast or counter balance which will effectually prevent the ship from tilting and turning over 100 in a high wind or storm.

From the foregoing description, taken in connection with the accompanying drawings, the construction and operation of the invention will be readily understood without requiring a more extended explanation.

Various changes in the form, proportion and the minor details of construction may be resorted to without departing from the principle or sacrificing any of the advantages of this invention as defined in the appended claims.

Having thus described my invention, what I claim is:—

1. A combined balancing and steering device for airships comprising a casing rectangular on its exterior and having a cylindrical bore, its upper and lower ends being reduced and made cylindrical, ferrules thereon, supporting bars in which said ferrules are journaled, the casing having oppositely disposed upright slots between said ferrules, a shaft slidably mounted in the casing and having lugs projecting through said slots, a combined balancing weight and rudder carried by said shaft, a guide block carried by one of said lugs and movable vertically outside the casing, a steering handle having a bifurcated head passing around the casing, a bolt connecting the arms of said bifurcation and spaced from the casing to permit the passage of the block between them, and means attached to the other lug for raising and lowering the shaft.
2. A combined balancing and steering device for airships comprising a casing rectangular on its exterior and having a longitudinal bore, its upper and lower ends being reduced and made cylindrical, ferrules thereon, supporting bars in which said ferrules are journaled, the casing having oppositely disposed upright slots between said ferrules, a shaft slidably mounted in the casing and having lugs projecting through said slots, a combined balancing weight and rudder carried by said shaft, a guide block carried by one of said lugs and movable vertically outside the casing, a steering handle having a bifurcated head passing around the casing, a bolt connecting the arms of said bifurcation and spaced from the casing to permit the passage of the block between them, the handle being provided with a slot on that side of the casing opposite said bolt, a pulley journaled on the upper support, and a cable passing over said pulley and attached to the other lug for raising and lowering said shaft and rudders,
- this lug and the lower end of the cable passing through the slot in the handle.
3. A combined balancing and steering device for air ships comprising a revolvably mounted upright tubular casing, supports therefor, a shaft slidably mounted in said casing, a combined balancing weight and rudder secured to the lower end of said shaft, a raising and lowering cable connected to said shaft, a guide pulley on the upper support to receive said cable whereby the same may be actuated to raise and lower said shaft and the weight and rudder and a handle adjustably secured to the casing between its supports and having a slot for the passage of said cable.
4. A combined balancing and steering device for air ships, comprising a casing having formed in two sides thereof oppositely disposed slots, and having its ends reduced to form cylindrical journals, supporting bars to receive said journals and revolvably support the casing, a shaft slidably mounted in the casing, lugs formed on said shaft and projecting through the slots in the casing, a guide block secured to one of said lugs, a raising and lowering cable secured to the other lug, a guide pulley to receive said cable, whereby the latter may be actuated to raise and lower said shaft, a combined balancing weight and rudder secured to the lower end of the cable and adapted to be raised and lowered thereby, and a handle having a bifurcated head adapted to be adjustably clamped to said casing whereby the same and said shaft may be turned to actuate said rudder and weight and thus steer the ship.

In testimony whereof I have hereunto set my hand in presence of the subscribing witnesses.

WILLIAM RANDOLPH SMITH.
